UNITED STATES PATENT OFFICE

VICTOR S. THARP, OF ELMHURST, ILLINOIS, ASSIGNOR TO RESERVE HOLDING COMPANY, OF CHICAGO, ILLINOIS, A CORPORATION OF DELAWARE

TELEPHONE SYSTEM

Application filed April 6, 1929. Serial No. 353,017.

The present invention relates to telephone systems in general, but is concerned more particularly with multi-office automatic telephone systems; and the broad general object 5 is the production of new and improved trunk circuits for use in connection with the inter-office trunk lines whereby a connection set up from an originating automatic exchange through a tandem automatic exchange to a toll board is maintained intact as long as the connection is maintained in an answered state by the operator at the toll board, even though the receiver is replaced at the calling substation.

15 A feature of the present invention is that the holding operation is carried out over a two-conductor trunk line without resorting to special ground connections or special battery connections at either end of the trunk line.

Other objects and features, which are more or less incidental to the foregoing, will become apparent upon a further perusal of the specification.

25 Referring now to the drawings comprising Figs. 1, 2, and 3, Figs. 1 and 2 show by means of the usual circuit diagrams certain apparatus of a telephone system embodying the features of the invention, and Fig. 3 shows 30 a desirable modification of the apparatus shown in Fig. 2.

The invention having been described generally a detailed description of the operation of the apparatus shown will now be given.

35 For the above purpose it will be assumed that the subscriber at the substation shown in the upper left hand corner of Fig. 1 desires to extend a connection which must be completed through the toll recording board 40 shown in Fig. 2.

Setting operation

When the receiver is removed at the calling substation, the line switch LS operates in the usual manner and extends the connection to the selector S¹.

45 When the first digit of the number assigned to the toll recording board is dialled, the selector S¹ responds in the usual manner 50 and extends the connection to an idle trunk

line in the required group, such as the trunk line TL¹, by way of a repeater, such as the repeater R. It will be assumed that the trunk line TL¹ is the first one found to be idle, and that it is consequently seized by way of 55 conductors 101, 102, and 103.

When the trunk line TL¹ is thus seized line relay 104 of the repeater R operates over conductors 101 and 103 and over the calling line and closes a circuit at its lower armature 60 for relay 111 by way of armature 113, normal. Relay 111 operates and at its upper armature places a ground potential on release trunk conductor 102 so as to form a holding circuit for the selector S¹ and for the line switch LS. 65 At its upper armature, relay 104 closes a bridge across the conductors of the trunk line TL¹, which bridge includes the upper and lower right-hand repeating-coil windings and the upper winding of relay 107, which 70 is shunted around the condenser 115 by way of the inner upper armature, normal, of relay 106. Relay 107 energizes in this bridge in series with the line relay (not shown) of the selector S² Fig. 2 and opens a point in the circuit 75 of relay 108, which would otherwise be closed at the inner lower armature of relay 107 through contacts of relays 111 and 106. It will be noted that the circuit for relay 111 is closed at the lower armature of relay 104 80 at the same time that the circuit for relay 107 is closed at the upper armature of relay 104. Consequently, relays 111 and 107 operate at about the same time. In case relay 107 operates slightly after relay 111 has operated, 85 relay 108 does not respond at this time owing to the fact that it is stiffly adjusted, which causes the actual operation of the relay to be delayed until the current has risen to almost its full value, which requires quite a 90 substantial fraction of a second.

The distant selector S² is prepared for operation in the usual manner responsive to the current flow over the trunk line TL in series with the line relay.

95 When the calling subscriber dials the second and last digit in the number assigned to the toll recording operator, the circuit of relay 204 is interrupted by the calling device CD a number of times corresponding to the 100

digit dialled. Each time its circuit is interrupted, relay 104 falls back and opens at its upper armature the bridge across the conductors of the trunk line TL with the result that 5 the distant selector S^2 is operated in the usual manner. At its lower armature, relay 104 opens the circuit of the slow acting release relay 11 each time it falls back, and it completes a circuit through the lower armature 10 of relay 111 and the lower armature of relay 106 for the series-responding relay 105. Relay 105 responds at the beginning of the series 15 of impulses, and, being slow-acting, remains operated throughout the series. Upon operating, relay 105 shunts the right-hand repeating-coil windings at its upper and lower armatures, and at its inner lower armature it 20 closes a holding circuit for relay 107 so as to maintain the relay operated while its circuit 25 is being interrupted at the upper armature of relay 104. It will be noted that relay 107 is provided with a copper sleeve surrounding its core, as indicated. This renders the relay slow in releasing so that it does not fall back 30 responsive to the opening of its circuit at the upper contacts of relay 104 before relay 105 responds to the closure of its circuit at the lower armature of relay 104 and closes the above-mentioned holding circuit for relay 35 107.

At the end of the digit, relay 104 comes to rest in an energized condition and relay 105 falls back. Relay 107 is held up through its upper winding.

35 In the tandem exchange, the selector S^2 responds to the second and last digit in the number by raising its wipers opposite the desired level of bank contacts and in searching for an idle trunk in the usual manner. It will be 40 assumed that the trunk line TL, reached by way of the trunk circuit TC^1 , is the first one found to be idle. In this case this trunk line is seized by the selector S^2 by way of conductors 201, 202, and 203. When this seizure 45 takes place, the circuit of relay 107 in the repeater R is transferred from the line relay (not shown) of the selector S^2 to line relay 204 of the trunk circuit TC^1 by way of conductors 201 and 203 and the left-hand repeating-coil windings and contacts of relay 206. Relay 107 remains energized in series with relay 204, and relay 204 operates and closes 50 a circuit for relay 209 and a parallel circuit for release relay 210 through contacts of relay 211. Relay 209 operates and reverses the connections between the inner right-hand repeating-coil terminals and the armatures of relay 211. Relay 210 places a holding ground potential on release trunk conductor 55 202 at its upper armature, and closes a circuit for relay 211 at its inner upper armature. Relay 111 operates and opens the initial circuit of relay 210 at its lower armature, leaving relay 210 held up at the lower armature of relay 209. Relay 211 also connects the wind-

ings of relay 212 to the inner right-hand repeating-coil terminals through the operated armatures of relay 209. As a result, the negative pole of battery is connected to the lower conductor of the trunk line TL^2 , and the positive pole of battery is connected to the upper conductor. This causes the polarized line relay 222 of the trunk circuit TC^2 , which is bridged around the condenser 223, to operate and close a circuit for lamp 225. Relay 225 closes a circuit for the line lamp 227.

70 Relay 212 in the trunk circuit TC^1 does not operate in series with the polarized relay 222 on account of the high resistance of the relay when both windings are connected in series.

Operator responds

75 When the operator notes the lighted condition of the lamp 227, she inserts the plug of an idle cord circuit into the jack 228. When she does so, current flows through the tip and ring conductors of the cord plug and through the right-hand repeating coil windings in series with the resistance 226, which is connected up at the inner contacts of relay 225. This gives the operator answering supervision at her cord circuit in the usual manner. At its upper armature, relay 221, 80 which is operated over the sleeve of the jack 228 from the sleeve of the plug, extinguishes the lamp 227 and at its inner armature it short circuits the high-resistance upper winding of relay 222. When this occurs, relay 212 of the trunk circuit TC^1 operates and completes 85 at its inner lower armature a holding circuit for relay 218 through the lower armature of relay 211. At its lower contacts, relay 212 closes a circuit for relay 206 through the lower armature of relay 210. Relay 206 operates 90 and locks itself at its own lower contacts independent of the lower contacts of relay 212. At its inner lower armature and its upper armature, relay 206 disconnects the incoming 95 conductors 202 and 203 from the windings of the battery-feed line relay 204 and connects them instead to the relay 205 through the middle upper armature of relay 210. Relay 204 accordingly falls back and opens the 100 circuit of relay 209, but relay 209 is now held operated through the middle lower armature of relay 206, the armature of relay 205, and the lower armature of relay 210. Relay 209 is thus held operated and it maintains relay 105 210 operated at its lower armature. In this way the connection is now held up even though there is no current flowing over conductors 201 and 203 subsequent to the disconnection of relay 204 by relay 206.

110 In the repeater R, relay 107 falls back as a result of the cessation of current flow over the conductors of the trunk lines TL^1 responsive to the operation of relay 206 of the trunk circuit TC^1 , and completes a circuit for re-

5 lay 208, which includes contacts controlled by armature 113 and the inner lower armature of relay 111. Upon operating, relay 108 closes a circuit for relay 110 at its upper armature through resistance 109. Relay 110 operates and closes a new circuit for relay 111 at its lower armature, while at its upper armature it closes a circuit for relay 106. Relay 106 operates and locks itself at armature 112 to the inner lower armature of relay 111; it shunts the upper contacts of relay 104 at its upper armature; opens a point in the circuit of relay 105 at its lower armature to prevent further operation of the said relay; and at armature 113 it opens the initial circuit of relay 111, which relay is now held operated by the lower armature of relay 110, and closes a circuit for relay 108, which includes the lower armature, operated, of relay 104 and armature 113, operated. At the same time, the initial circuit of relay 108 is opened by the contacts controlled by armature 113.

25 As the circuit now stands in the repeater R, the line relay 104 is held energized over the calling line and is holding the relay 108 operated. Relay 108 is controlling relay 110 and is at present holding it operated through the local resistance 109. Relay 110 is holding relay 111 operated, which relay in turn is holding the locking circuit of relay 106 closed.

35 The conversation between the calling subscriber and the toll recording operator may now proceed. The calling subscriber may ask for a connection which may be set up right away, in which case the connection is completed through the toll recording switchboard, but if the subscriber asks for a connection that cannot be set up immediately, the toll recording operator records the calling and called numbers and the calling party is recalled later by the toll operator.

45 *Recalling the operator*

For convenience in making the explanation which is to follow, it will be assumed that the toll recording operator extends the connection and that, while the connection is being extended, the calling party desires to converse again with the toll recording operator. In order to attract the attention of the toll recording operator, the calling subscriber pushes his switchhook down and allows it to come up again, repeating this a few times in the usual and well known manner. Each time the switchhook is pushed down at the calling substation, line relay 104 falls back and opens the circuit of relay 108 at its lower armature. Relay 108 falls back and opens the local circuit of relay 110 through resistance 109, but it completes a new circuit for relay 110 over the conductors of the trunk line TL¹. The lower winding of relay 110 is connected to the lower conductor of the trunk line

70 through the lower contacts of relay 106 and the lower right-hand repeating-coil winding; while the upper winding of relay 110 is connected to the upper conductor of the trunk line TL¹ by way of the normally closed contacts controlled by the upper armature of relay 108, inner upper armature of relay 106, upper right-hand repeating-coil windings, and the upper contacts of relay 106.

75 When relay 110 is thus connected to the trunk line TL¹, current flows over the trunk line TL¹ from the relay 110 and passes through relay 205 which is bridged around the condenser 207 through contacts of the operated relays 206 and 210. Upon operating, relay 205 opens the circuit of relay 209. When relay 209 falls back it reverses the connection between the windings of relay 212 and the conductors of the trunk line TL², with the result that the polarized line relay 222 85 restores. When it does so, relay 225 deenergizes and opens the supervisory bridge through the resistance 226, causing the supervisory lamp to become lighted in the operator's cord circuit.

90 When the receiver hook is permitted to rise at the calling substation, relay 104 operates again and closes a circuit through armature 113, operated, for relay 108. Relay 108 operates and closes a loop circuit for relay 110 95 through resistance 109, opening the circuit of the relay over the trunk line TL. When this occurs relay 205 of the trunk circuit TC¹ falls back and again closes the circuit of relay 209, whereupon relay 209 reoperates and reverses the connections between the conductors of the trunk line TL² and the windings of the relay 212. The polarized line relay 222 100 in the trunk circuit TC² now responds and again operates relay 225 to restore the operator's cord circuit to the state of answered supervision.

105 The foregoing operations are repeated each time the switchhook is depressed and permitted to rise.

110 *Release of connection*

115 When the calling subscriber replaces his receiver at the end of the conversation, the operations herein before described in connection with signalling the operator by depressing the switchhook are repeated, and the operator's supervisory lamp lights as a disconnect signal.

120 When the operator takes down the connection, relay 221 falls back and reinserts the high-resistance upper winding of relay 222 into the circuit. When this occurs relay 212 in the trunk circuit TC¹ falls back and opens the circuit of release relay 210. Release relay 210 falls back a moment later and opens the circuit of relay 205 at its middle upper armature, whereupon relay 205 falls back; at its inner upper armature it opens the circuit of relay 211; and removes ground from the 125 130

release trunk conductor 202 at its upper armature. When this occurs, the selector S^2 releases. The circuit of relay 203 is opened at the lower armature of relay 210 with the result that relay 206 falls back, restoring the trunk circuit to its normal condition.

In the repeater R^1 , relay 110 falls back responsive to the opening of its circuit over the trunk line TL^1 at the middle upper armature of relay 210. Upon restoring, relay 110 opens the circuit of relay 111, with the result that relay 111 falls back a moment later and removes ground at its upper armature from release trunk conductor 102. This permits the line switch LS and the selector S^1 to release. Relay 111 at its inner lower armature opens the circuit of relay 106 and that relay falls back.

The connection is now completely released and the apparatus involved therein is ready to be used in subsequent connections.

Alternative releasing operation

It will now be assumed that the connection is set up and that the operator has responded in the manner hereinbefore described and that the operator pulls down the connection before the receiver is replaced at the calling substation. When this occurs, relay 212 of the trunk circuit TC^1 falls back responsive to the reinsertion of the upper high resistance winding of relay 222 into its circuit, and it opens the circuit of relay 210 at its inner lower armature as in the releasing operation previously described. In this case, however, relay 210 does not release but is held operated by the lower armature of relay 209. Relay 209, it will be recalled, is now operated in a circuit including the lower winding of relay 210, lower armature of relay 205, and the middle lower armature of relay 206.

Now when the receiver is replaced at the calling substation under this condition, relay 104 falls back and relay 108 falls back as a result and reconnects relay 110 to the conductors of the trunk line TL^1 . Relay 205 energizes in series with relay 110 and opens the circuit of relay 209. Relay 209 falls back and opens the circuit of relay 210 at its lower armature. Relay 210 falls back and brings about the release of the selector S^2 at its upper armature, at the same time opening the circuit over the trunk line TL^1 for relay 110 at its middle upper armature.

The restoration of the repeater R and the release of the line switch LS and the selector S^1 take place as hereinbefore described.

Description of the modified circuits

Referring now particularly to Fig. 3, the modified circuits shown therein will be explained. The trunk circuit TC^3 is employed in the place of the trunk circuit TC^1 , and the trunk circuit TC^4 is employed at the toll board in place of the trunk circuit TC^2 . It

will be observed that the trunk line TL^3 , which takes the place of the trunk line TL^2 , is a three-conductor trunk line. This comes about because it is assumed that the toll board is located in or near the exchange containing the trunk circuit TC^3 , in which case, it is considered economical to use a third conductor in the trunk line and simplify the trunk circuit TC^3 . It has been chosen to illustrate the trunk circuit TC^4 as one giving supervision through the combined call and disconnect lamp 326 in addition to relaying it into the cord circuit as is the case of the trunk circuit TC^2 of Fig. 2.

The detailed description of the operation of the apparatus shown in Fig. 3 will now be given. For this purpose it will be assumed that the trunk circuit TC^3 is seized by a selector, such as the selector S^2 of Fig. 2 over the conductors 301-303. When this occurs, a circuit is closed over conductor 302 through the test wiper of the seizing selector for relay 304. This comes about because the slow-acting release relay in a selector holds up momentarily after its circuit has been opened upon the switching-through operation of the selector. As long as the release relay of the selector holds up, the test wiper is maintained grounded from within the selector. Upon operating, relay 304 prepares a locking circuit for itself at its upper armature and at its lower armature prepares a holding circuit to be hereinafter traced.

As a further result of the seizure of the trunk circuit TC , a circuit is closed over the incoming talking conductors 301 and 303 in series through the left-hand repeating-coil windings, normally closed contacts controlled by armatures of relay 309, right-hand repeating-coil windings, upper and lower conductors of the trunk line TL^3 , left-hand repeating-coil windings of the trunk circuit TC^4 , and through the windings of the line relay 321. The line relay 321 operates and at its upper armature places ground on the release trunk conductor of the trunk line TL^3 , closing a circuit for relay 309 of the trunk circuit TC^3 . Relay 309 operates and extends the grounded release trunk conductor of the trunk line TL^3 to the incoming release trunk conductor 302 through the contacts of relay 304. This closes a holding circuit for maintaining relay 304 operated, and for holding the seizing selector in an operated condition. As a further result of its operation, relay 309 disconnects the inner terminals of the right-hand repeating-coil windings from the corresponding terminals of the left-hand repeating-coil windings and completes a bridge across the conductors of the trunk line TL^3 through the upper right-hand repeating-coil winding, condenser 307 and resistance 308 in parallel, contacts of relays 304 and 305, lower armature of relay 309, and the lower right-hand repeating-coil winding. This bridge

maintains relay 321 of the trunk circuit TC^4 operated. At the same time, a bridge excluding battery and ground connections is closed across the conductors 301 and 303 through the 5 upper left-hand repeating-coil winding, inner upper armature of relay 309, the condenser 306 and relay 305 in parallel, and the lower left-hand winding of the repeating coil. No current flows through the bridge at this time and the current flow over conductors 10 301 and 303 accordingly ceases. This causes the preceding repeater, such as R, Fig. 1, involved in the connection to switch over in the manner pointed out hereinbefore 15 responsive to the answering of the call by the operator.

As a further result of the energization of line relay 321 of the trunk circuit TC^4 , a circuit for the line lamp 326 is closed at the inner 20 upper armature of the relay through contacts of sleeve relay 325.

When the operator responds to the lighted condition of the lamp 326 by inserting the plug of an idle cord circuit into the jack 327, 25 relay 325 pulls up over the sleeve of the plug in use and of the jack 327, and at its upper armature makes a second ground connection to the associated release trunk conductor, and at its inner armature it opens the circuit 30 of the lamp 326. A bridge is now closed across the tip and ring conductors of the jack through both right-hand windings of the repeating coil, through the condenser 323 and the resistance 324 in parallel and contacts 35 of relay 321. This bridge permits current to flow, which passes through resistance 324, giving the operator answering supervision in her cord.

Recall

40 In case the calling subscriber manipulates his switchhook to signal the operator after the operator has responded, the application of current to conductors 301 and 303 by the repeater in use, such as the repeater R, Fig. 1, 45 through the windings of the holding relay, such as the relay 110, results in the operation of relay 305 of the trunk circuit TC^3 . When relay 305 operates it opens the circuit of line 50 relay 321. When line relay 321 falls back it closes a circuit for the lamp 326 at its inner upper armature, signalling the operator. At its lower armature it opens the bridge across the tip and ring conductors of the jack, causing 55 the supervisory lamp in the cord circuit to flash. The release trunk conductor of the trunk line TL^3 is maintained grounded at this time at the upper armature of sleeve relay 325. When the switchhook is allowed to rise 60 at the calling substation and the potential is removed from conductors 301 and 303 by the reoperation of the control relay, relay 305 of repeater R, relay 305 falls back and again closes the circuit for relay 321. Relay 65 321 reoperates and extinguishes the lamp

326 at its inner upper armature and gives answering supervision at the cord circuit at its lower armature.

Release

70 Assuming now that the calling subscriber replaces his receiver, the disconnect signal is given by means of the lamp 326 responsive to the operation of relay 305 and the consequent reenergization of relay 321. The disconnect signal is also given in the cord circuit due to the opening of the lower contacts of relay 321.

75 When the operator pulls down the connection, relay 325 falls back and removes ground from the associated release trunk conductor at its upper armature, whereupon relays 308 and 309 restore and the preceding selector releases. Relay 305 falls back when relay 309 restores. The trunk circuits TC^3 and TC^4 80 are now in normal condition and the repeater R clears out and permits the preceding switches to release in the manner hereinbefore described.

85 It may be pointed out that the function of relay 304 is to condition the circuit so that the accidental grounding of release trunk conductor 302 or the accidental manipulation of any one of the relays of the trunk circuit TC^3 will not result in a locked up condition 90 of the circuit as would be the case if relay 304 were omitted.

95 What is claimed is:

1. In a telephone system, a repeater, a 100 two-conductor trunk line, means including automatic switching apparatus for extending a connection to said trunk line by way of said repeater, other automatic switching apparatus operable over said trunk line by impulses repeated at said repeater to extend a connection from said trunk line to a called line, said impulses comprising interruptions in current flowing in a circuit including the two conductors of the trunk line in series, means effective 105 after the connection has been extended to the called line for closing a circuit for holding the said switching apparatus independent of further current flow over said trunk line and for stopping the current flow over said trunk line, and means for maintaining the current flow stopped regardless of the condition of the called line.

110 2. In a telephone system, a trunk line extending from a first exchange to a second exchange, means including automatic switching apparatus in the first exchange for extending a connection to said trunk line, automatic switching apparatus in the second exchange, means responsive to the seizure of said trunk line by the automatic switching apparatus at the first exchange for setting up a 115 current flow thereover from a current source in the second exchange, means at the first exchange for interrupting the current flow over said trunk line to operate the auto- 120

matic switching apparatus in the second exchange to set up a connection from the trunk line, means effective after the connection is set up for stopping the current flow over the trunk line by cutting out the current source in the second exchange, and means in the first exchange for transmitting a signal to the second exchange by associating a current source in the first exchange with said trunk line to set up a current flow thereover.

3. In a telephone system, a trunk line extending from a first exchange to a second exchange, means including automatic switching apparatus in the first exchange for extending a connection to said trunk line, automatic switching apparatus in the second exchange, means responsive to the seizure of said trunk line by the automatic switching apparatus at the first exchange for setting up a current flow thereover from a current source in the second exchange, means at the first exchange for interrupting the current flow over said trunk line to operate the automatic switching apparatus in the second exchange to set up a connection from the trunk line, means effective after the connection is set up for stopping the current flow over the trunk line by cutting out the current source in the second exchange, means in the first exchange for transmitting a signal to the second exchange by associating a current source in the first exchange with said trunk line to set up a current flow thereover, means in the second exchange for opening the trunk line to stop the flow of current thereover, and means in the first exchange responsive thereto for releasing the said automatic switching apparatus in the first exchange.

4. In a telephone system, a trunk line, means for setting up a current flow over said trunk line and for interrupting the current flow, means at the distant end of the trunk line including automatic switching apparatus responsive to the interruptions in the current flow for extending a connection from the trunk line, means for stopping the current flow over the trunk line, and means thereafter effective to release the automatic switching apparatus in the second exchange responsive to further current flow over said trunk line, and means controlled over the connection set up through the automatic switching apparatus for preventing the release from being effected responsive to said current flow.

5. In a telephone system, an inter-exchange trunk line extending from a first exchange to a second exchange, means for seizing said trunk line and for setting up a current flow thereover, means in the first exchange for interrupting the current flow, automatic switching apparatus in the second exchange responsive to said interruptions to extend a connection from the trunk line to a called line, means for stopping the current flow over said trunk line after the connection has

been extended, means responsive to further current flow over said trunk line controlled from the first exchange for releasing the automatic switching apparatus in the second exchange, and means controlled over the called line for preventing the said release of the automatic switches.

6. In a telephone system, an inter-exchange trunk line extending from a first exchange to a second exchange, means for seizing said trunk line in the first exchange, for setting up a current flow thereover, and for interrupting said current flow, means in the second exchange including automatic switching apparatus responsive to said interruptions for setting up a connection from the trunk line to a called line, means effective when a response is secured on the called line for stopping the current flow over said trunk line, means controlled from the first exchange for causing further current flow over said trunk line, means in the second exchange for causing the called party to be signalled by the further current flow, and means for releasing the automatic switches responsive to said further current flow in case the called party has disconnected from the called line.

In witness whereof, I hereunto subscribe my name this 3d day of April, A. D. 1929.

VICTOR S. THARP.
